UNITED STATES PATENT OFFICE.

FREDERICK V. JONES, OF ZYLONITE, MASSACHUSETTS, ASSIGNOR TO THE ZYLONITE COMB AND BRUSH COMPANY, OF SAME PLACE.

DESIGN FOR A COMB.

SPECIFICATION forming part of Design No. 16,681, dated May 11, 1886.

Application filed April 5, 1886. Serial No. 197,893. Term of patent 14 years.

To all whom it may concern:

Be it known that I, FREDERICK V. JONES, a citizen of the United States, residing at Zylonite, in the county of Berkshire and State of Massachusetts, have invented and produced a new and original Design for Combs, of which the following is a specification.

This design has for its object to provide a new and original toilet-comb which is ornamental and very attractive.

The design consists in a comb having the back, to which the teeth are joined, extended into the form of the handle of a handsaw.

In the accompanying drawings, illustrating my invention, Figure 1 is a plan view of a comb made in accordance with my design, and Fig. 2 a similar view showing a variation in the form of the comb.

Referring to the drawings, the numeral 1 indicates the comb-back, and 2 the teeth. The comb-back at one end is extended longitudi-

nally, as at 3, and such extension terminates in the form of a handle of a handsaw, as at 4. The grasping part 5 of the handle, as here shown, is curved and formed with ribs or projections 6.

The comb may be formed with the points of the teeth on a line parallel to the comb back, as in Fig. 1, or the comb may be tapering, as in Fig. 2.

Having thus described my invention, what I claim is—

The design for a comb having a back, to which the teeth are joined, extended into the form of the handle of a handsaw, substantially as shown and described.

In testimony whereof I affix my signature in presence of two witnesses.

F. V. JONES.
